UNITED STATES PATENT OFFICE.

AUGUSTINE J. POCOCK, OF DAYTON, OHIO.

OPERATING MECHANISM FOR SWITCHES.

1,128,505.

Specification of Letters Patent.

Patented Feb. 16, 1915.

Application filed July 5, 1913. Serial No. 777,598.

To all whom it may concern:

Be it known that I, AUGUSTINE J. POCOCK, a citizen of the United States, residing at Dayton, in the county of Montgomery and State of Ohio, have invented certain new and useful Improvements in Operating Mechanisms for Switches; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in operating mechanism for switches.

The object of the invention is to provide a switch operating mechanism of simple construction and desirable efficiency; one that will effectually control the circuit without causing arcs to form at the terminals, and will permit the circuit to be opened or closed at different pressures.

Referring to the accompanying drawings, Figure 1 is a top plan view of the device; Fig. 2 is a section on the line *a—a* of Fig. 1; Fig. 3 is a section on the line *b—b* of Fig. 2; and Fig. 4 is a section on the line *c—c* of Fig. 3.

In the specification and drawings, similar reference characters indicate corresponding parts.

Referring more particularly to the drawings, 1 represents a frame plate provided with a horizontal right angled extension 2. Secured to the said extension 2 is a block of suitable insulating material 3 upon which are, in turn, mounted resilient bars 4. The said bars 4 are attached to the insulating blocks 3 by means of bolts 5 which are provided with binding screws 6 to which lead wires are attached. The free ends of the bars 4 are provided with pockets 7 which receive terminal blocks 8. The blocks 8 are in positions to be engaged by contact members 9, thereby forming a well known type of electrical switch. The insulating block 3 is provided with pockets 3^a beneath the bars 4 which permit said bars to bend and the terminal blocks 8 to adjust themselves to the contact members 9, thus securing an effective contact. I do not wish to limit myself to this particular type of switch as any well known type of either single or

double break switch may be provided. The contact members 9 are mounted on an insulating block 10 attached to one end of an arm 11 pivoted at 12 to the frame 1. The said contact members 9 are provided with binding screws 13, and the leads therefrom, and those from the binding screws 6 may extend through openings 14 in a wall 15 attached to the frame 1 and extension 2. The said leads are connected to the source of electrical energy and the motor in the usual manner. The upward movement of the arm 11 and the contact members 9 which are carried thereby is limited by a stop 16 mounted on an adjustably sliding member 17 secured to the frame 1. The stop 17 limits the movement of the lever 19 in one direction, while the terminal blocks 8 act as stops and limit the movement of said lever in the other direction. The arm 11 is elevated and lowered under the influence of fluid pressure, such as water under pressure or compressed air, as follows. The said arm 11, which, it will be observed, is bifurcated, carries an antifriction roller 18 which is adapted to be engaged by the two inclined surfaces 19 and 20 of a catch lever 21. The said lever 21 is pivoted at 22 to one end of a lever 23 and is under the control of a spring 24. One end of the said spring 24 is connected to the lever 23, while the other end of said spring is connected to the end of the lever 21 opposite the inclined surfaces 19 and 20.

In the position the parts are shown in the drawings, the lower inclined surface 20 is in engagement with the roller 18 of the pivotal arm 11, thereby permitting the spring 24 to press the lever 21 downward upon said roller. When the lever 21 is lowered, as presently described, the upper inclined surfaces 19 will engage the roller 18 and will elevate the arm 11, thereby opening the switch. The lever 23 is pivoted at 25 to the frame 1, and the end of the lever 23 opposite the lever 21 is connected at 26 to a plunger or rod 27. Said rod 27 extends through an adjusting nut 28 and into a cylinder 30 where it engages a diaphragm 31 which is mounted between a flange 32 of the cylinder 30 and a cap 33. The said cap 33 is provided with an opening 34 which receives a pipe or tube 35 leading from a reservoir (not shown) and which receives the fluid discharged by the pump (not shown) and which, as before

stated, is controlled by the switch. The pressure in the reservoir influences the diaphragm 31. When this pressure rises, the diaphragm 31 will rise against the tension of a spring 36 within the cylinder 30, around the rod 27 and between the diaphragm and the adjusting nut 28. The rise of the diaphragm causes the lever 21 to lower, and the inclined surface 19 thereon engages the 10 roller 18 and thereby elevates the arm 11, thus separating the terminal blocks 8 and the contact members 9. It will be noted that when this separation takes place, the action will be practically instantaneous, 15 thereby preventing arcing at the terminal blocks and contact members. When the pressure in the reservoir decreases, the spring 36 elevates the lever 21 and places the lower inclined surface 20 in contact with 20 the roller 18, thereby permitting the spring 24 to depress the arm 11 and close the circuit. It will be noted that the greater the extent of movement of the arm 11, as determined by the stop 16, the greater will 25 be the extent of movement of the diaphragm 31 necessary to move the lever 21 to elevate and lower the arm 11. Consequently, the difference in pressure between that at

which the pump starts and that at which it stops is determined by the stop 16. The 30 pressure at which the pump stops and at which the circuit is broken is determined by varying the tension of the spring 36 by the nut, while the difference in pressure between that at which the pump starts and 35 when it stops is determined by the stop 16.

Having described my invention, I claim:

In a device of the character specified, the combination with a lever, and a roller mounted thereon, of stops for said lever 40 one of which is adjustable with reference thereto, a second lever having inclined portions engaging said roller and controlling the position of said first named lever between said stops, a third lever upon which 45 said second named lever is fulcrumed, and means for actuating said third named lever, whereby the second named lever is caused to move across the plane of the first named lever. 50

In testimony whereof I affix my signature, in presence of two witnesses.

AUGUSTINE J. POCOCK.

Witnesses:

R. J. McCARTY.

MATTHEW SIEBLER.
